UNITED STATES PATENT OFFICE

WARREN T. REDDISH, OF CINCINNATI, OHIO, ASSIGNOR TO EMERY INDUSTRIES, INC., OF CINCINNATI, OHIO, A CORPORATION OF OHIO

METHOD OF CLEANING FABRICS

No Drawing.

Application filed February 4, 1932. Serial No. 590,981.

This invention relates to a new art, method, and process of cleaning garments, fabrics, textiles, cloth, rugs and articles of like nature which, for the sake of convenience, throughout the remainder of the description, will be designated by the term "fabrics" unless otherwise specifically identified.

In view of the fact that the invention lends itself to being practiced in so-called dry cleaning establishments, on the classes of articles usually cleaned there and with the types of equipment usually used there, the present invention is described and claimed as an improvement in the "dry cleaning" art. However, the physical chemistry utilized in practicing this invention and the results obtained, are so contrary to the principles and go so far beyond results now designated by the term "dry cleaning", that one might classify the fabric cleaning development of this invention as an entirely new art.

In order to comprehend the true novelty of principle of this invention, a brief review of the theories of previously known methods of cleaning fabrics is requisite. Cleaning fabrics has been accomplished in the past either by a soap and water process or by the dry cleaning process. The dry cleaning process differs in principle from the wet washing process.

In the wet washing process the dirt particles on the fabric are removed by emulsification and saponification of the oils and greases which bind the particles to the fabric. This is usually accomplished by washing the fabrics with the ordinary fatty acid soaps which possess emulsifying powers in water solution and liberate alkali by hydrolysis which combines with the saponifiable oils present. These fatty acid soaps also lower the surface tension of the solution which accelerates the detergent action by increasing the rate of penetration of the soap and water into the fabric. The highly water soluble soil which may also be present is removed, of course, by the solvent action of the water. This process is injurious to a majority of types of fabric because it often causes shrinkage, fading or disfigurement.

In the dry cleaning industry to which this

invention is directed, a conventional cleaning solvent is employed of the type exemplified by a volatile hydrocarbon or chlorinated hydrocarbon, the more commonly used of which are gasoline, naphtha, carbon tetrachloride and trichlorethylene. At present, the dry cleaning process is usually practiced by treating the fabrics in rotating drum type washers containing the cleaning solvent to which may be added suitable so-called dry cleaning soaps which decrease static and lower surface tension. The agitation is continued for from ten to thirty minutes, depending upon the type of fabrics being treated and their condition. During this treatment, the oily or greasy film, which binds the dirt particles to the fabrics, is dissolved and the dirt particles are removed by the agitation of the fabrics in the solvent. The articles are then rinsed in clean solvent and centrifugally extracted and then dried either in rotary drum type dryers or in heated rooms. By this treatment oily and greasy soil is removed without shrinkage of the fabric or damage to the sizing and finishing materials, the dyes or the fibre itself.

However, marks or disfigurements called "water spots" which are caused by water having come in contact with the fabric and roughened or partially dissolved the finishing material and spots caused by solely water soluble substances, such as perspiration, soft drinks, sugar syrups, and the like, are not removed by this process. It is, therefore, necessary to employ water or other suitable solvents to remove them. This is usually done by hand spotting of the affected local areas in order that the amount of water coming in contact with the fabric may be kept down to a minimum. Due to the labor involved, this operation is relatively expensive compared to the rest of the process. Moreover, the results obtained depend upon the skill of the worker and, at best, are highly unsatisfactory.

Such spots may in some cases be removed by what is called the wet-dry treatment in which the fabric is first immersed in the cleaning solvent and then, while still saturated with solvent, treated with cold water

or a dilute soap solution for from three to five minutes. The presence of the cleaning solvent in the fabric prevents the absorption of sufficient water to cause appreciable shrinking, loss of sizing material or bleeding of colors, but allows the water to come in contact with the soluble spots sufficiently to bring about their solution. This process is tedious, expensive, and may injure a fabric or fail to 5
remove the spots, or both. Obviously, both hand spotting and the wet-dry methods are make-shifts dependent upon artizan skill and judgment. It is, therefore, to be observed at this point that there is no existing process 10
15 for cleaning fabrics which is inherently adapted to be used on all types of fabrics to remove all types of soil.

It has always been customary (and still is), to clean fabrics made from vegetable fibres 20 such as cotton and linen goods, by washing in soap and water. This process can also be used on some articles of wool, silk and rayon, but very great care is required, and generally speaking, the fabrics made from fibre of 25 animal or synthetic origin, which are adapted to the soap and water washing process, are the exception rather than the rule.

Most of the outer garments worn in this country at present, such as suits, dresses, 30 coats, etc., are made from fibres of animal origin, usually silk or wool, or both. Such articles are ruined in appearance by soap and water washing. As a result of the development of cheap cleaning solvents in the last 35 half of the last century, and as a result of the shifting of population to the large urban centers in which more formal attire prevails, the central dry cleaning plant came into being and its facilities became widely available.

40 The ubiquity of the dry cleaning plants permitted the designers of fabrics to develop a great many new sizing and finishing materials, special weaves, peculiar thread twists, and many new and brilliant dyestuffs, 45 which in cleaning would require the special skill and equipment of the large central dry cleaning establishments. On this account, the so-called dry cleaning process has become a tremendous national industry despite the 50 fact that it does not remove water marks and is inherently adapted to remove from the fabrics but one class of soil, that is, the oil soluble soil, as distinguished from perspiration and other types of water soluble soil.

55 The object of this invention is to provide an entirely new and novel art, method or process by means of which fabrics are cleansed of substantially all varieties of spots or soil without individual attention to each article 60 treated or the utilization of artizan skill and judgment.

This invention resides in a series of recognitions, concepts and determinations which have required and received verification by 65 large scale commercial operation upon all

classes of fabrics normally tendered to dry cleaning establishments throughout the different seasons of the year during which temperature, humidity, the type of garments worn, and the fabrics employed vary substantially.

These recognitions, concepts and determinations are as follows: An optimum cleaning action on fabrics is provided by a cleaning solvent containing a substantial, determined and controlled quantity of absorbed moisture. If the moisture be dispersed throughout the cleaning solvent to a very extreme degree, for instance, that degree which is signified by a substantial optical clarity of the solution, then the moisture will not have its usual deleterious effects upon the fibre, the dyestuff, or the finish of the fabric being treated. In other words, even the finest silk evening dress will not be injured by this treatment.

Thus, it is possible to remove the water soluble spots or soil with a quantity of dispersed moisture which is not injurious to the fabric being treated, or vice versa, a quantity of finely dispersed moisture, so small that it does not injure the fabric being treated, has the capacity to remove the water soluble spots and soil. Still otherwise expressed, the invention resides in the concept and determination that an appropriate amount of moisture appropriately dispersed throughout a dry cleaning solvent, possesses the desirable cleaning properties of water but not the disadvantages.

The next feature of this invention, which is rather unexpected, is that the quantity of moisture adapted to produce the best results should be determined and controlled primarily in relation to the weight of the fabrics treated, rather than in relation to the weight or quantity of the cleaning solvent used. This is due to the fact that the fabrics always absorb substantially all of the moisture in the cleaning solvent. Therefore, the quantity of moisture contacted with the fabrics or transferred to the fabrics in the process, is the critical factor rather than the ratio of moisture to cleaning solvent in the bath in which the fabrics are treated. However, the amount of moisture to be used in practicing this invention must not exceed the moisture tolerance of the type of fabric being cleaned.

The more specific aspects of the invention may be said to reside in the determination that a useful cleaning action is obtained by agitating the fabrics in a body of cleaning solvent containing about five percent of their weight of moisture and that in many cases, the weight of moisture may be increased to thirty percent of the weight of the fabrics without injury thereto. For instance, silk garments may be cleaned by treatment with between five and fifteen percent of their weight of moisture, though approximately

- ten percent is recommended for most large scale commercial runs which include numerous evening gowns. In the case of men's suits, ten to thirty percent of their weight 5 of moisture may be used in the cleaning solvent, though fifteen percent seems to produce the best average results on a batch of winter suits collected from a high class suburban neighborhood.
- 10 It is obvious that if a fine satin evening dress were treated in a bath in which water and naphtha were simply churned up together, the dress would become hopelessly water spotted because of large drops of water 15 absolutely saturating the dress in many local areas. Such an undesirable effect diminishes in proportion to the fineness of the particles of water. Even a coarse emulsion would ruin a silk dress because the emulsion would 20 saturate completely certain local areas with water and other local areas with the naphtha. If, however, the dispersion of the moisture in the naphtha is so fine that the solution is substantially optically clear, then the absorption 25 of moisture by the fabric being treated is more analogous to the absorption of moisture by a fabric in a very damp climate, for instance, on the seashore.
- This new process in which a fabric is 30 treated with and takes on between five and thirty percent of its weight of moisture, under normal conditions, (a large group of fabrics being churned about in a container of cleaning solvent and moisture), results in 35 the removal from the fabrics of water soluble soil such as syrup spots, perspiration marks, soft drink spots, and the like, as well as all oily or greasy soil. Moreover, water spots disappear from the fabric and many types 40 of finish, in general use at present, seem to be not only completely restored and renovated, but improved by this treatment, so that the fabrics look as well or even better than they did when new.
- 45 In view of the fact that moisture does not admix readily with the cleaning solvents in common use at present, absorbefacients must be used—(these will be described at a later point). While the moisture for the first 50 batch of fabrics may be added to the cleaning solvent directly with the absorbefacient, it is believed to be better practice and more in conformity with the spirit of this invention first to add the absorbefacient to the cleaning 55 solvent and thereby create in this cleaning solvent the capacity to absorb the substantial and requisite quantities of moisture in a state sufficiently fine and dispersed as not to be injurious to the fabrics to be treated. Then 60 the desired quantity of moisture may be determined and added for each batch of fabrics treated. This step is termed "charging" the cleaning solvent.
- It is recommended that the cleaning solvents be constituted water absorbent for the 65 maximum amount of moisture requisite for the impending operations. If this be done, then it is not necessary to adjust the ratio of absorbefacient to cleaning solvent for particular or unusual conditions which may arise. 70
- In commercial operations, each batch of fabrics to be cleaned is weighed. Generally speaking, fifty or sixty pounds of fabric are considered the maximum load for about fifty gallons of cleaning solvent. The cleaning 75 solvent is charged with moisture, the amount being based upon the weight of fabrics being treated. In this connection, attention should be paid to the humidity of the atmosphere which normally determines the percentage 80 of moisture already in the fabrics. Likewise, it is necessary to take into account the nature of the fabrics being cleaned and the degree of soil.
- It is obvious, of course, that fabrics affected by a large amount of exclusively water soluble spots or soil, require treatment with larger quantities of moisture to effect removal 85 than do fabrics having a small amount of soil of this type. When men's rough clothes or the like are being treated, it is possible, if desired, to incorporate so much moisture either before the treatment or during the treatment, 90 that the cleaning solvent becomes murky without injuring the fabrics, though in the case of ladies' fine silk dresses and articles of like nature, injury is almost sure to occur if the dispersion or moisture be coarse. It must be remembered in this regard, that the optical 95 properties of the solution are mentioned solely for the purpose of indicating the degree of subdivision or dispersion of its moisture content, and that these optical properties have no merit or virtue in and of themselves. 100
- In many climates and cases it is desirable to dry out the fabrics before they are treated, as this step permits the transfer of a larger quantity of moisture to the fabric and hence 105 provides a greater cleaning effect for a given final moisture content of the fabric in question. For instance, if silk garments are being treated and the final moisture content is substantially over fifteen percent, then difficulty is often experienced in the pressing room 110 because of wrinkling. Such garments, however, can be entirely satisfactorily cleaned and pressed first by drying them out, then treating them with about ten percent (based on the weight of the fabrics) of moisture incorporated in the cleaning solvent. 115
- The preferred process, as a series of steps, 120 comprises: first, drying out the fabric to be cleaned, if necessary. Next, the fabrics are weighed. Next, they are given a preliminary dip in a straight solution of cleaning solvent to get off the worst of the dirt and saturate the fibres with cleaning solvent. Next, 125 moisture is introduced into a second batch of cleaning solvent to be used for the crucial 130

treatment, the amount of moisture used being approximately equal to between five and thirty percent of the weight of the fabrics being treated. Ten percent is recommended for 5 fine silks and fifteen percent for men's suits.

After this the fabrics are agitated and churned about in this cleaning bath for a period of between fifteen minutes and half an hour, depending upon the fabrics and 10 their condition. It is highly desirable to filter the cleaning solvent during this cleaning process, in order to prevent dirt particles being loosely deposited upon the fabrics as they are removed from the bath. In view of 15 the fact that most of the filters in use for this purpose do not permit moisture to pass through them, it is recommended that this filtering be confined to approximately the last quarter of the treatment inasmuch as by 20 that time substantially all of the moisture present has been absorbed by the fabrics being cleaned.

It is of great importance that the absorbefacients employed in the process have the 25 capacity to pass the filters in solution. Otherwise the process would not be adapted for use in the modern, well-equipped dry cleaning plants, in practically all of which filtration during treatment is standard practice. The absorbefacient, therefore, must 30 form in the cleaning solvent a stable, permanent, solution which will pass the filters, will not settle out, or change chemically or 35 physically in such wise as to lose its requisite colloidal properties.

The fabrics are next given a rinse in cleaning solvent after which they are dried and subjected to relatively routine handling. 40 The filtration of the cleaning solvent containing the absorbefacient may be continued after the removal of the fabrics until the cleaning solvent is clarified to the desired extent. As pointed out previously, the 45 amount of moisture added must be determined and calculated in relation to the weight and nature of the next batch of fabrics. After the cleaning solvent accumulates too great an amount of oil soluble soil or contamination to be clarified and purified by filtration, it is distilled and a new 50 moisture absorbent solution constituted.

As far as is known, it is necessary to use absorbefacients in all of the cleaning solvents at present available to endow them with the 55 properties requisite for the practice of this invention. These properties desirable for the cleaning solvent include: filterability (in the absence of moisture); power and capacity to repeatedly absorb substantial quantities of moisture in a state of subdivision so fine 60 that the solution is substantially optically clear; chemical inertness towards all varieties of fibres, dyestuffs, sizes and finishes; 65 physical and chemical stability.

The problem of constituting such a clean-

ing solvent is believed to be, at present, beyond the ordinary skill of colloidal chemists, and surely beyond the skill of the dry cleaning industry. Therefore, for the purpose of assisting the skilled in the art in practicing 70 this invention, a number of formulae for absorbefacients is provided. Claims, however, directed to the specific absorbefacients and to their physical and chemical actions, are reserved for co-pending applications inasmuch as the principles involved are susceptible 75 to useful employment in many different arts in addition to that of cleaning fabrics. The claims in the present case are, therefore, limited entirely to the art, or method or 80 process of cleaning fabrics herein disclosed. These formulae of absorbefacients are as follows:

	(1)	Per cent	85
Commercial sulfonated castor oil containing 31% water		30	
Oleic acid		21	
Potassium oleate		9	
Water		3	
Naphtha		29.5	
Hexa hydro phenol		7.5	
		100.0	90

The ratio of blending agent to cleaning solvent can be varied, but a 10% concentration is recommended.

	(2)	Per cent	95
Commercial sulfonated castor oil, 15% water content		50	
Oleic acid		50	

A 16% by weight concentration in cleaning naphtha gives a clear solution which re-absorbs moisture, but the mix is cloudy in 100 concentrations below and above 16%.

	(3)	Per cent	
Sodium salt of sulfonated oleic acid naphthalene, condensation product — neutralized Twitchell reagent		42.8	105
Sodium oleate		22.0	
Oleic acid		22.0	
Ethylene glycol, mono-butyl-ether		13.2	

A 10% solution of the above formula in cleaning naphtha produces a cleaning solvent capable of containing 1% moisture. The 110 percentage concentration of this absorbefacient in the cleaning solvent is critical.

	(4)	Per cent	115
Hydrogenated sulfonated anthracene		14.5	
Naphtha		40.5	
Oleic acid		17.5	
Water		15.0	
Sodium oleate		12.5	

An 8% concentration in naphtha is recommended. After being depleted of moisture, the solution re-absorbs it, but considerable agitation is required.

	(5)	Per cent	
Sulfonated hydrogenated anthracene		7.55	125
Naphtha		21.00	
Oleic acid		25.60	
Water		11.75	
Potassium oleate		26.25	
Mono-butyl-ether of ethylene glycol		7.85	

This formula absorbs moisture very readily and its concentration in the naphtha solution 120

is not critical. A 10% concentration is recommended.

(6)

	Per cent
Oleic acid	25
Naphtha	25
Pure mahogany sodium sulfonate	50

This material re-absorbs the moisture readily and can be used in any cleaning solvent suitable for dry cleaning in almost any proportions. A recommended concentration 10 is 6%.

(7)

	Per cent
Oleic acid	35.3
Naphtha	35.3
Cyclohexanol	17.6
Potassium hydroxide	5.3
Water	8.5
Triethanolamine	3.0

A 6% solution is suitable for absorbing the usually desirable amounts of moisture.

(8)

	Per cent
Oleic acid	30.0
Naphtha	45.0
Butyl ethylene glycol mono ethyl ether	15.0
Potassium hydroxide	5.0
Water	5.0

A 6% solution is suitable for absorbing the usually desirable amounts of moisture.

These various formulæ exhibit to varying degrees the properties of the ideal absorbefacient to be used in practicing this invention. Certain ones of the absorbefacients 30 tend to cause bleeding of certain dyestuffs on some fabrics but are entirely satisfactory for other classes of articles. The use of some of the absorbefacients would require appreciable expert control of the conditions 35 of the cleaning process to insure best results or would be usable only where this control was available.

Of the various formulæ provided, No. 6 is the preferred and recommended one because 40 it possesses all of the requisite properties previously discussed, can be used with all of the types of cleaning solvents at present employed for dry cleaning, can be used safely and successfully on a commercial scale with- 45 out supervision of the cleaning process by skilled chemists, and can be used successfully on all types of fabrics adapted to be cleaned by this general process.

Moreover, formula No. 6 may be used in 50 most dry cleaning plants as at present constituted without any substantial changes of equipment or material changes in handling and routing the fabrics through the plant except as herein specified.

55 Formulæ Nos. 7 and 8 are characterized by very ready absorption of moisture and are suitable for use for fabric cleaning purposes without the exercise of an undue amount of chemical control. These formulæ are char- 60 acterized by the use of partially saponified oleic acid and a material or reagent mutually miscible with oil and water. This re- agent may be termed an absorption assist- ant. Cyclohexanol is the absorption assistant 65 of formula No. 7 and butyl ethylene glycol

mono ethyl ether of formula No. 8. Other mutually miscible materials which may be used as absorption assistants, (though with varying degrees of safety on dyed fabrics), comprise butyl acetate, isopropyl alcohol, 70 ethyl alcohol, di-acetone alcohol, ethylene glycol mono ethyl ether acetate, and diethylene glycol mono butyl ether. Absorption assistants which tend to be taken up by the fabrics must be periodically replenished. 75

In regard to these formulæ Nos. 7 and 8, it must be noted that the presence of free fatty acid is desirable to render a fatty acid soap truly soluble in the cleaning solvent in the presence of moisture and that the absorption assistants augment the power to take up the required quantities of moisture rapidly and in the proper condition of dispersion.

This application is a continuation in part of my previous co-pending application Serial No. 492,611, which discloses the water dispersing action of mahogany sulfonates and several of the other absorbefacients and one use of this dispersing action in the cleaning of fabrics. Mahogany sulfonates 90 are the salts of mahogany acids which are formed in the oil layer or A layer in the refining of medicinal white oil and the like by the use of fuming sulfuric acid and/or sulfur trioxide. The United States Patent to 95 Divine, No. 1,493,111, issued May 6, 1924, discloses mahogany sulphonate bodies suitable for the practice of this process.

Great care must be used in employing this invention with chlorinated cleaning solvents 100 to avoid the formation of harmful quantities of hydrochloric acid and therefore throughout this description the invention has been disclosed in relation to the equipment of an open, naphtha process plant, though it must be understood that other types of equipment and plants may be used with appropriate minor modifications well within the skill of the art.

All claims directed to the specific absorbefacients and their use, as well as claims directed to the improvement of the appearance of silks and wools are being prosecuted in copending divisional applications. 110

Having described my invention, I desire to 115 be limited only by the ensuing claims:

1. In the dry cleaning art, the process which comprises cleaning fabrics with a dry cleaning solvent of the type exemplified by a volatile hydrocarbon or chlorinated hydrocarbon which is moisture absorbent by reason of an absorbefacient dissolved therein and which contains an amount of moisture determined in relation to the weight and nature of the batch of fabrics being cleaned, but does not exceed the moisture tolerance 120 of the fabrics.

2. In the dry cleaning art, the process which comprises cleaning fabrics with a dry 125 cleaning solvent of the type exemplified by a

volatile hydrocarbon or chlorinated hydrocarbon which is moisture absorbent by reason of an absorbefacient dissolved therein and which contains an amount of moisture 5 determined in relation to the weight and nature of the batch of fabrics being cleaned, but does not exceed the moisture tolerance of the fabrics, the moisture in the cleaning liquid being so finely dispersed that the liquid is substantially optically clear.

3. In the dry cleaning art, the fabric cleaning process which comprises preparing a moisture absorbent cleaning liquid by dissolving an absorbefacient in a dry cleaning 15 solvent of the type exemplified by a volatile hydrocarbon or chlorinated hydrocarbon, charging the liquid so constituted with moisture each time a batch of fabrics is cleaned therein, the amount of the charge in each 20 case determined in relation to the weight and nature of the fabrics constituting the specific batch, but in no case exceeding the moisture tolerance of the fabrics and treating the fabrics with the liquid so constituted to remove 25 greasy soil and water soluble soil concurrent- ly in one operation.

4. In the dry cleaning art, the fabric cleaning process which comprises preparing a moisture absorbent cleaning liquid by dissolving an absorbefacient in a cleaning solvent 30 of the type exemplified by a volatile hydrocarbon or chlorinated hydrocarbon, forming a substantially optically clear dispersion of moisture in the liquid so 35 constituted each time a batch of fabrics is cleaned therein, the amount of the charge in each case determined in relation to the weight and nature of the fabrics constituting the specific batch but in no case exceeding 40 the moisture tolerance of the fabrics and treating the fabrics with the liquid so constituted to remove greasy soil and water soluble soil concurrently in one operation.

5. The process of cleaning successive 45 batches of fabrics in a body of dry cleaning solvent of the type exemplified by a volatile hydrocarbon or chlorinated hydrocarbon, said process comprising rendering the cleaning solvent, moisture absorbent by dissolving 50 ing an absorbefacient therein and cleaning the successive batches of fabrics in said body of solvent, the cleaning of each batch being accompanied by the charging of the cleaning solvent with an amount of moisture equal to 55 between 5 and 30% of the weight of the fabrics constituting the specific batch, the exact amount of moisture depending upon the tolerance of the fabrics constituting the batch.

6. The process of cleaning successive 60 batches of fabrics in a body of dry cleaning solvent of a type exemplified by a volatile hydrocarbon or chlorinated hydrocarbon, said process comprising rendering the cleaning solvent moisture absorbent by dissolving 65 an absorbefacient therein and cleaning the

successive batches of fabrics in said body of solvent, the cleaning of each batch of fabrics being accompanied by the charging of the cleaning solvent with moisture, the amount of moisture in each instance, being within 70 the limitation of the moisture tolerance of the particular batch, whereby the removal of the batch removes from the solvent substantially the moisture content previously added.

In witness whereof, I hereunto subscribe 75 my name.
